Specification for Design.

Patented Jan. 20, 1914.

Application filed November 19, 1913. Serial No. 801,996. Term of patent 3½ years.

To all whom it may concern:

Be it known that I, JOHN H. HAWLEY, a citizen of the United States, residing at No. 179 West Seventy-ninth street, in the borough of Manhattan, city, county, and State of New York, have invented a new, original, and ornamental Design for Buttons, of which the following is a specification, reference being had to the accompanying drawing, forming part thereof.

In the said drawing: Figure 1 is a top

plan view of a button embodying the design. Fig. 2 is a side elevation thereof, and Fig. 3 is a vertical sectional view taken through Fig. 1.

I claim:

The ornamental design for a button, substantially as shown.

JOHN H. HAWLEY.
